UNITED STATES PATENT OFFICE.

RANSOM Y. BOVEE, OF MAYWOOD, ILLINOIS, ASSIGNOR TO AMERICAN CAN COMPANY, OF NEW YORK, N. Y., A CORPORATION OF NEW JERSEY.

HOLDER FOR ROLLS OF TOILET-PAPER.

1,322,524.

Specification of Letters Patent. Patented Nov. 25, 1919.

Application filed December 7, 1916. Serial No. 135,533.

To all whom it may concern:

Be it known that I, RANSOM Y. BOVEE, a citizen of the United States, residing in Maywood, in the county of Cook and State 5 of Illinois, have invented a new and useful Improvement in Holders for Rolls of Toilet-Paper, of which the following is a specification.

This invention relates in general to a 10 holder for rolls of toilet paper and the like and has for its object broadly the provision of a simple, effective and improved structure capable of economical manufacture.

A principal object of the invention is the 15 provision of a holder for toilet paper and the like which will permit a roll of toilet paper to be readily put in place and which will at the same time restrain the roll against excessive unwinding.

Another object of the invention is the provision of a holder for rolls of toilet paper and the like so constructed that the roll may not be removed after once being positioned until the paper is exhausted, thereby preventing 20 robbery of the rolls when the fixtures are used in public comfort stations and the like.

A further object of the invention is the provision of such a holder which will be 25 constructed entirely of sheet metal, the parts of which may be readily and cheaply formed.

Other objects and advantages of the invention will be apparent as it is better understood from the following description when considered in connection with the accompanying drawing illustrating a preferred embodiment thereof.

On the drawing,
40 Figure 1 is a top plan view of a holder embodying my invention with parts shown in section;

Fig. 2 is a transverse vertical sectional view of the same;
45 Fig. 3 is a partial similar view with the parts somewhat differently arranged to disclose the operation of securing the roll in place; and

Fig. 4 is a view showing a preferred 50 means of holding an end of the roll in one of the fixed arms.

For the purpose of illustrating my invention I have shown on the drawing a holder embodying it and comprising a back 10, two

arms 11 and 12, a cylindrical member 13 55 and a pressure member 14, all of simple construction. The back, in the present instance, is constructed of a single piece of sheet metal having its edges 15 formed into an outwardly extending peripheral flange 60 adapted to rest against a wall to which the holder may be fastened. The body 16 of the back is spaced away from the wall by this flange and is depressed at appropriate locations 17 and slotted at 18 in such de- 65 pressions to receive the holding device 19. At each end two lugs 21 are struck up to provide bearings for pivots 22 on which pivots the arms 11 and 12 are mounted.

Each of these arms in the present instance 70 consists of a single sheet of metal having a circular end 23 and a body 24. A peripheral flange 25 extends along both sides of the body 24 and about the end 23. This flange is extended at its bottom at 26 to form a lug 75 bearing upon the outer face of the back when the arms are in operative position, as shown in full lines in Fig. 1. The body of the arm is curved outwardly at 27 to cover the hinged connection with the lugs 21. The 80 provision of the lugs 21 provides apertures through the back plate and the edges of these apertures serve to limit the outward pivotal movement of the arms as indicated in Fig. 1, the body 24 being cut away at 28 85 to leave ends 29 adapted to pass through the recesses in this movement.

The portion 25 of the flange which is disposed about the circular end of each arm is, of course, of arcuate form and extends 90 throughout considerable more than a semi-circumference. Inwardly of the center of the circular end the flanges are provided with oppositely disposed inwardly extending lugs 95 31 forming shoulders for engagement with the connecting member 13 as will be presently described.

The connecting member is composed of the substantially cylindrical body 13 and the pressure member 14 each of which is preferably composed of a single sheet of metal. An end of the cylindrical member 13 is made compressible so that it may be engaged with the shoulders or lugs 31. In the present instance this is accomplished by making the 100 entire cylindrical member so that it may be squeezed to smaller circumference and the end moved past the shoulders, subsequent 105

expansion seating the lugs in suitable apertures in the sheet. The sheet 13 in the present instance is bent to cylindrical form with its side edges 32 unconnected, spaced apart and drawn inwardly as shown. Near one end a pair of apertures 33 are formed in appropriate position to receive the lugs 31. The normal diameter of the cylinder is such as to cause it to fit snugly within the annular portion of the flange 25 with the lugs 31 resting in the apertures 33. The end which is detachably engaged with the arm 12 is tapered slightly at its extremity in order to facilitate insertion in the flange of the arm, the other end or the one engaged with the arm 11 may or may not be compressible and may be fastened to the arm 11 in any desired way. However I prefer to provide lugs 41 like the lugs 31 adapted to enter apertures 43 like the apertures 33. This end of the cylindrical member or body 13 can be then positioned, whether compressible or not, by tilting the same with respect to the arm, first threading the lugs 25 through the apertures and then bringing the body to the position shown in the drawing. To hold it firmly and finally in this position I provide a third lug 44 at the outer end of the arm adapted to be bent 30 through an aperture 45 formed for the purpose in the body to lock the two together. This arrangement fastens the body 13 to the arm 11 permanently and without any lugs or other parts appearing upon the outside to mar the appearance.

Two T-slots 34 are formed in the sheet 13 and in these T-slots rest T-lugs or ears 35 on the edges of the curved plate forming the pressure member 14. This plate is given 40 a cylindrical curvature different from the cylindrical curvature of the cylinder 13, preferably being of less radius. Its tendency, therefore, is to bow out pressing upon the cardboard core of the roll of toilet paper. It may be positioned by merely inserting the heads of the lugs 35 through the heads of the T-slots 34 and when so positioned is in no danger of being disconnected unless it is desired to remove it. The cylinder 13 may be formed with a depression to receive the member 14.

It will be manifest from the foregoing that a roll of toilet paper positioned in a holder embodying the present invention will 55 be restrained from unrolling, except in accordance with the continued pulling on the loose end, the pressure member 14 preventing too great unwinding. When a roll has been exhausted it is only necessary to tear 60 away a part of the core, which is ordinarily stiff, then to compress the end of the cylindrical body engaging the arm 12 thus freeing it from this arm and permitting the core to be removed and a second roll to be positioned. The tapered end can then be in-

serted in the flange and the parts snapped together to cause the lugs to seat in the apertures.

It is thought that the invention and many of its attendant advantages will be understood from the foregoing description, and it will be apparent that various changes may be made in the form, construction and arrangement of the parts without departing from the spirit and scope of the invention 75 or sacrificing any of its material advantages, the form hereinbefore described being merely a preferred embodiment thereof.

I claim:

1. A holder for a roll of toilet paper and the like comprising a pair of arms adapted to extend out from a wall, a member disposed between said arms and on which the roll is adapted to turn in unwinding, said member being provided with a friction plate 85 having its end yieldingly connected with said member and its middle portion outwardly movable for restraining undesired movement of said roll.

2. A holder for a roll of toilet paper and the like comprising a pair of arms adapted to extend out from a wall, one of said arms being movable and having lips extending toward each other, and a member adapted to extend between said arms, said member comprising a metal sheet bent to cylindrical form and having apertures near an end to receive said lips, said end of said member being compressible to permit said lips to pass into and out of said apertures. 100

3. A holder for a roll of toilet paper and the like comprising a supported cylindrical member, and a friction element extending circumferentially of said cylindrical member to prevent undesired unwinding of said 105 roll, an end of said element having a sliding interlocking connection with said member.

4. A holder for a roll of toilet paper and the like comprising a supported cylindrical member, a metal sheet curved on smaller radius than said cylindrical member and having its ends interlocked in said cylindrical member and being adapted to be pressed toward said cylindrical member by the core 110 of a roll of toilet paper carried thereby. 115

5. A holder for a roll of toilet paper and the like comprising a supported cylindrical sheet metal member having a slot in its side, a sheet metal member curved similarly and of radius different from that of said supported member, and an end of said second mentioned sheet metal member being slidably engaged in said slot and adapted to restrain rotation of a roll of toilet paper in said holder. 120

6. A holder for a roll of toilet paper and the like comprising a pair of arms adapted to extend out from a wall, one of said arms having a flange annularly about its end, a cylindrical carrying body having an end 130

adapted to be inserted in said annular flange, said end being provided with perforations and said flange having a plurality of lugs extending radially inwardly and disposed through apertures to lock the end of the body to said arm. 5 and said flange having a plurality of lugs extending radially inwardly and disposed through apertures to lock the end of the body to said arm, one of said lugs being bendable in position after said arm is engaged with said body. 15

7. A holder for a roll of toilet paper and the like comprising a pair of arms adapted to extend out from a wall, one of said arms having a flange annularly about its end, a 10 cylindrical carrying body having an end adapted to be inserted in said annular flange, said end being provided with perforations

Signed in the presence of two subscribing 20
witnesses.
